CLAIM

The ornamental design for a printer, as shown and described.

DESCRIPTION

FIG. 1 is a front perspective view of a printer showing our new design;

FIG. 2 is a front view thereof;

FIG. 3 is an enlarged view of a portion indicated by lines 3a-3a' and line 3b-3b' in FIG. 2;

FIG. 4 is a rear view thereof;

FIG. 5 is a top plan view thereof;

FIG. 6 is a bottom plan view thereof;

FIG. 7 is a right side view thereof; and,

FIG. 8 is a left side view thereof.

The broken lines depict environment as well as the bounds of the enlargement, and form no part of the claimed design. In addition, the unshaded surface that immediately adjoins the claimed solid line edge forms no part of the claimed design.
